JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

DOBBY FOR LOOMS.

Application filed February 6, 1926. Serial No. 86,520.

The present invention relates to an improvement in dobbies for looms.

The object of the invention is to reorganize and improve the construction of doby mechanism in order to facilitate changes in the operation of the loom, and to this end the invention consists in the mechanism hereinafter described and particularly defined in the claims.

10 In the accompanying drawings illustrating the preferred form of the invention, Fig. 1 is an elevation of the doby fingers and its connections with the doby hooks and doby levers by which the harness jacks 15 are operated; and Fig. 2 is a plan of the doby finger arrangement.

The illustrated embodiment of the invention is described as follows:—The doby fingers 10 are pivotally mounted on the finger shaft 11, supported in the frame members 12. This finger shaft is held in position by a set screw 13, the shaft being received in bosses in the frame members 12. A supporting member 14 for the free ends of the 25 fingers 10 is provided, with a series of guide pins 15, which engage the reduced portions 16 at the ends of the fingers to guide the fingers up and down in their movements by the doby chain, the cams of which engage the portion 17 of the fingers. The left-hand ends of the doby fingers, as shown in Fig. 1, are arranged so that some of them are provided with the upwardly extended doby hook lifting arms 18, which engage the lower 30 doby hooks 19, and others of the doby fingers are provided with the arms 20, upon which the push rods 21 rest, which are employed to lift the upper doby hooks 22. The doby hooks 19 and 22 are pivotally mounted on the ends of the doby levers 23, which are pivoted at 24 to the harness jacks 25. The doby girts 26 and 27 are of the usual form.

The construction thus far described may 45 be of any usual or preferred construction.

The doby fingers require re-arrangement at times for the purpose of changing the control of the harness jacks for weaving different types of cloth. When this is to be 50 done, the finger shaft 11 is loosened and

withdrawn. Heretofore this freed all of the doby fingers, which were then removed to a bench or other convenient place for rearrangement in the new order or series. It is desirable to make these changes in the 55 doby fingers without removing them from the doby frame, and to this end a rod 28 is provided in the doby frame, which engages a groove in the under side of the doby fingers near the finger shaft. This permits 60 the withdrawal of the finger shaft without disturbing the doby fingers from their normal position, and permits the re-arrangement of the doby fingers without taking them out of the doby frame. This support 65 rod 28 comprises a support for the doby fingers for holding them in unchanged position, i. e., from longitudinal movement and from falling movement when the finger shaft to which they are normally pivoted is re- 70 moved from the machine, and affords access to the fingers for removal, replacement or re-arrangement in a convenient manner.

Having thus described the invention, what 75 is claimed is:

1. A doby for looms having, in combination, doby fingers, a doby frame, a finger shaft supported in the frame, upon which the doby fingers are pivotally mounted, an end supporting member for the doby fingers, and an auxiliary finger support for supporting the doby fingers in unchanged 80 position when the finger shaft is removed.

2. Dobby mechanism for looms having, in combination, a plurality of doby fingers, 85 a doby frame, a finger shaft upon which the doby fingers are pivotally supported, removably secured in the frame, an end support for the doby fingers, an auxiliary support for the doby fingers located between 90 the finger shaft and the end support, and at such a position between the two that the center of gravity lies between the auxiliary support and the end support, the doby fingers being provided with a recess to receive the 95 auxiliary support, and being so shaped as to restrain the doby fingers from movement when the finger shaft is removed.

3. Dobby mechanism for looms having, in combination, a plurality of doby fingers, a 100

finger shaft upon which the fingers are said recesses in the fingers to support them pivotally mounted, a frame carrying the finger shaft provided with an end support for the free ends of the dobby fingers, said fingers being provided with a recess in their under side, an auxiliary finger support carried by the dobby frame adapted to engage

in unchanged position when the finger shaft is removed.

In testimony whereof I have signed my name to this specification.

JONAS NORTHROP.
